UNITED STATES PATENT OFFICE.

ERNA HABBEMA-HORAK, OF ENSCHEDE, NETHERLANDS.

HAT-FASTENER.

No. 857,392.

Specification of Letters Patent.

Patented June 18, 1907.

Application filed December 6, 1906. Serial No. 346,525.

To all whom it may concern:

Be it known that I, ERNA HABBEMA-HORAK, (married,) a citizen of the Netherlands, and a resident of Enschede, Netherlands, have invented certain new and useful Improvements in Hat-Fasteners, of which the following is a specification.

This invention relates to improvements in fasteners for ladies' hats, and has for its object to provide a device which can be used in place of the old-style hat pins.

In the drawings accompanying this specification and forming part of same, in which like reference letters denote like parts wherever they occur, Figure 1 is a front view of the device; Fig. 2 is a side view; and Fig. 3 is a detailed view of one form of fastening which is used.

The clasp *a* is made of a thin sheet of any flexible material, such as metal, rubber, celluloid, or the like. The ends thereof are narrow, so that they may pass through the hair easily, while the middle part is made fairly broad, as a fastener so constructed not only 25 presents a more handsome appearance, but, in addition, can be held in place more securely than would be the case if the clasp *a* were of uniform width throughout.

To each end of clasp *a* is fastened, by 30 means hereinafter described, the stud half *b* of an ordinary stud-and-socket button, such as is commonly used to fasten gloves, said stud being composed of a plurality of out-flaring spring-like pieces which are pressed 35 inwardly by the walls of the socket as the stud *b* is inserted therethrough, but which spread outwardly again as they reach the cavity in the center of the socket half *c* of the button, thereby holding the two parts *b* and 40 *c* together.

To the inner sides of the hat are fastened short ribbons *d*, and upon these ribbons *d* are mounted the socket halves *c* of the buttons, or, if so desired, the sockets *c* can be secured 45 directly to the hat in any convenient manner.

Clasp *a* is so constructed that it may be placed upon the wearer's head before the hair is dressed, so that the clasp *a* is covered over and concealed by the hair, or it may be 50 placed in position after the hair is dressed, the ends of clasp *a* being made thin and narrow, so that they will readily pass through the hair. When the clasp *a* is to be thus used, at least one of the studs *b* must be detachable from said clasp, for, otherwise, the stud *b* would catch in the hair and prevent 55

the clasp from being placed in position or withdrawn therefrom after the hair is dressed. To the end of clasp *a* from which it is desired to have stud *b* detachable, a piece *e* of sheet 60 metal or other spring-like material is secured, preferably so as to be flush with the surface of clasp *a* but projecting slightly beyond the end thereof, which projecting end is provided with an offset *f*. A U-shaped 65 spring-clamp *g*, from which stud *b* projects outwardly, is forced over the end of clasp *a* and the spring *e* attached to said end, and, thereupon, offset *f* seats in a recess provided in clamp *g*, thus securing clamp *g* and the 70 stud *b* borne thereby upon clasp *a*. When it is desired to remove clamp *g*, to allow the clasp *a* to be withdrawn from the head, or for any other purpose, clamp *g* can be pulled off of clasp *a*, as spring *e* will yield sufficiently to 75 allow offset *f* to ride out of the recess in clamp *g* in which said offset seats. Both ends of clasp *a* may, of course, be provided with detachable studs, and in some cases this construction will be found preferable.

As hereinabove stated, clasp *a* may be placed in position either before or after the hair is dressed, but when it is once adjusted in place all that remains to be done is to press the studs *b* into the sockets *c*, and the 85 hat will be held in place upon the wearer's head.

While reference has herein been made only to one particular form of button-connection between the clasp *a* and the hat, it should be 90 understood that such form is given merely as an example, and that any other securing device will answer the same purpose.

Various other modifications may be made without departing from the spirit of the invention. The clasp *a*, for example, may be very artistically designed, so that it will be a handsome ornament when the hat is removed, and, similarly, the studs *b* can be shaped as rosettes or the like, so that their 95 real purpose will not be too evident.

Having thus described my said invention, what I claim and desire to secure by Letters-Patent is:

1. A hat fastener comprising a clasp fitting 105 over the wearer's head, a spring secured to the end of said clasp, and a fastener-bearing member passing over the end of said clasp and held in place by said spring.

2. A hat fastener comprising a clasp fitting 110 over the wearer's head, a spring secured to the end of said clasp, an offset upon said

spring, a fastener-bearing member passing over the end of said clasp, and a recess in said member in which said offset seats.

3. A hat fastener comprising a clasp fitting over the wearer's head, a spring secured to the end of said clasp, an offset upon said spring, a fastener-bearing member passing over the end of said clasp, a recess in said member in which said offset seats, ribbons secured to the hat, and means upon said ribbons engaging the fastener carried by said member.

4. A hat fastener comprising a **U**-shaped clasp of flexible sheet material, said clasp being held in place beneath the hair of the wearer, a spring secured to the end of said clasp, a fastener-bearing member passing over the end of said clasp and held in place by said spring, and means carried by the hat engaging the fasteners borne upon said fastener-bearing member.

5. A hat fastener comprising a **U**-shaped clasp of sheet material, said clasp being held in place beneath the hair of the wearer, a stud borne by said clasp, and a socket borne by the hat, said stud being inserted in said socket, thereby to hold the hat fixed upon the head.

6. A hat fastener comprising a **U**-shaped clasp of sheet material, a fastener borne upon the end of said clasp but detachable therefrom, and means carried by the hat and engaging said fastener.

7. A sheet-material clasp held in place by the hair of the wearer, studs borne upon the ends of said clasp but detachable therefrom, and sockets carried by the hat and engaging said studs.

8. A sheet-material clasp held in place by the hair of the wearer, said clasp having tapering ends but a broad middle portion, detachable fasteners on the ends of said clasp, and means carried by the hat to be secured to said fasteners.

9. A sheet-material clasp held in place by the hair of the wearer, said clasp having tapered ends but a broad middle portion, a fastener-support placed on said ends, and locking-means to hold said fastener support on said clasp.

Signed at Amsterdam this 17 day of November 1906.

ERNA HABBEMA-HORAK.
